UNITED STATES PATENT OFFICE.

EMERALD E. JONES, OF CHICAGO, ILLINOIS, ASSIGNOR TO SURTY GUARD COMPANY,
A CORPORATION OF ILLINOIS.

GUARD FOR WOODWORKING-MACHINES.

1,119,612.

Specification of Letters Patent.

Patented Dec. 1, 1914.

Application filed March 16, 1914. Serial No. 824,999.

To all whom it may concern:

Be it known that I, EMERALD E. JONES, a subject of the King of Great Britain, and a resident of the city of Chicago, county of 5 Cook, and State of Illinois, have invented certain new and useful Improvements in Guards for Woodworking-Machines, of which the following is a specification.

My invention relates to guards for wood 10 working machines and more specifically to a device designed for use upon machines of this character to protect the hands of the operator against injury through contact with the cutting element of the machine.

15 The object of my invention is the production of a guard of the character mentioned which will be adapted for both transverse and vertical movement in order to permit of the work passing either at the inner 20 end thereof or under the guard, depending upon the character of the work which is being acted upon.

A further object is the production of a 25 guard as mentioned which will be of durable and economical construction and which by reason of the movement permitted the same, as just mentioned, will be of high efficiency in use.

Other objects will appear hereinafter.

30 With these objects in view my invention consists in the combinations and arrangements of parts hereinafter described and claimed.

The invention will be best understood by 35 reference to the accompanying drawings forming a part of this specification, and in which,

40 Figure 1 is a top plan view of a wood working machine equipped with a guard embodying my invention, Fig. 2 is a front elevation of the construction shown in Fig. 1, and Fig. 3 is an enlarged detail section taken on substantially line $x-x$ of Fig. 1.

45 Referring now to the drawing I have shown therein a wood working machine of conventional design consisting of a table 1 at the rearward edge of which is provided the work guide or fence 2. Arranged intermediate the ends of the table 1 is the rotary 50 cutting element 3 which protrudes through a transversely extending opening or slot 4 provided in the table top as shown.

The guard which coöperates with the cutting element 3 consists in its preferred form 55 of an elongated substantially rectangular

plate 5 which is transversely curved or arched in order to span the opening 4 and guard the blades of the cutting element 3 without contacting therewith. Said guard plate 5, when in use, is normally positioned 60 with its longitudinal edges contacting with the upper side of table 1 at either side of opening 4.

The outer end of guard plate 5 is pivotally connected at 6 with the corresponding 65 ends of elongated tubular arms 7 which extend substantially horizontally along the front edge of table 1, said arms being spaced from and disposed parallel with each other. The opposite ends of said arms are pivotally connected at 8 with a member 9 which is secured to the outer end of a stud 10 the rearward end of which is rockingly mounted in bearing lugs 11 projecting from a plate 12 which is secured by bolts 12' to one end 70 of table 1.

With the arrangement set forth it will be seen that the arms 7 are so connected with the table 1 as to permit of vertical swinging thereof about the stud 10 and horizontal 80 swinging about the pivotal points 8. This being so it will be seen that the guard plate 5 is so supported as to permit of free vertical as well as transverse movement relative to the table 1. Also the arrangement is such that said plate will normally assume a position at its lower terminal of vertical movement or in contact with the table 1 by gravity. A helical tension spring 13 arranged between the arms 7 and connected 85 at its respective ends with said arms serves to normally hold the guard plate 5 at its inner terminal of horizontal or transverse movement, said plate being however only yieldingly held so as to permit of free movement either vertically or transversely.

Provided at the inner end of guard plate 5 is a deflector bar 14 having a laterally and forwardly inclined surface 14' for engagement by work A passed through the machine over the table 1 in order to move or deflect the guard plate 5 laterally or transversely so as to permit of the passage of the work as will be readily understood. Also provided at the inner end of guard plate 5 is a bar 15 the under side 15' of which as well as that of the bar 14 being inclined forwardly and upwardly, as clearly shown in Fig. 2 for engagement with work B which is passed through the machine over the table 1 in 100 105 110

order to move the guard plate vertically to permit of the passage of the work as will be readily understood. A brace rod 16 coöperates with the bars 14 and 15 for reinforcement. The rearward or inner ends of all of said bars are connected with the guard plate by screws, and the inner ends of bars 14 and 15 are preferably countersunk in the under side of said guard plate as clearly shown in Fig. 3. With this arrangement then it will be seen that the guard will be deflected laterally by work which is comparatively high and narrow and vertically by work which is comparatively wide and low or thin, the cutting element, with this arrangement, being guarded by the plate 5 at all times.

While I have illustrated and described the preferred form of construction for carrying my invention into effect, this is capable 20 of variation and modification without departing from the spirit of the invention. I, therefore, do not wish to be limited to the precise details of construction set forth, but desire to avail myself of such variations and 25 modifications as come within the scope of the appended claims.

Having described my invention what I claim as new and desire to secure by Letters Patent is:

30 1. The combination with the table and cutting element of a wood working machine, of a guard arranged above said cutting element; a connection between said guard and said table permitting of free movement of 35 said guard vertically and transversely of said table, said connection comprising a pair of arms having corresponding ends mounted to permit of vertical and horizontal swinging of said arms; and a pivotal connection between the opposite ends of said 40 arms and said guard, substantially as described.

2. The combination with the table and cutting element of a wood working machine, 45 of a guard arranged above said cutting element and adapted normally to rest upon said table; a connection between said guard and said table permitting of free movement of said guard vertically and transversely of 50 said table, said connection comprising a pair of substantially horizontally disposed elongated spaced parallel arms having corre-

60 gated spaced parallel arms having corresponding ends mounted to permit of vertical and horizontal swinging of said arms; a pivotal connection between the opposite ends of said arms and said guard; and resilient means connected with said arms to normally yieldingly hold said guard at its inner terminal of transverse movement, substantially as described.

65 3. The combination with the table and cutting element of a wood working machine, of a guard arranged above said cutting element and adapted normally to rest upon said table; a connection between said guard and said table permitting of free movement of said guard vertically and transversely of 70 said table, said connection comprising a pair of substantially horizontally disposed elongated spaced parallel arms having corresponding ends mounted to permit of vertical and horizontal swinging of said arms; a pivotal connection between the opposite ends of said arms and said guard; and a helical tension spring arranged between and having 75 its opposite ends connected respectively with said arms for normally yieldingly holding said guard at its inner terminal of transverse movement, substantially as described.

80 4. The combination with the table and cutting element of a wood working machine, of a guard arranged above said cutting element; a connection between said guard and said table permitting of free movement of 85 said guard vertically and transversely of said table, said connection comprising a pair of arms having corresponding ends mounted to permit of vertical and horizontal swinging of said arms; a pivotal connection between the opposite ends of said arms and 90 said guard; and vertically and horizontally inclined work deflecting surfaces provided at the inner end of said guard, substantially as described.

95 In testimony whereof I have signed my name to this specification in the presence of two subscribing witnesses.

EMERALD E. JONES.
